UNITED STATES PATENT OFFICE.

FREEMAN HANSON, OF BAR MILLS, ASSIGNOR OF TWO-THIRDS TO H. AND W. J. KNOWLTON, OF PORTLAND, MAINE.

DANGER-SIGNAL.

SPECIFICATION forming part of Letters Patent No. 506,175, dated October 3, 1893.

Application filed December 13, 1892. Serial No. 455,066. (No model.)

To all whom it may concern:

Be it known that I, FREEMAN HANSON, a citizen of the United States, residing at Bar Mills, in the county of York and State of Maine, have 5 invented certain new and useful Improvements in Danger-Signals; and I do hereby declare the following to be a full, clear, and exact description of the invention, such as will enable others skilled in the art to which it ap-

10 pertains to make and use the same.

Figure 1 is a broken perspective view of this device. Fig. 2 is a side elevation, broken, showing the signal wound up. Fig. 3 is a detail in section through an end of one of the 15 standards and clasp and spring. Fig. 4 is a cross section through the extended signal, showing also the side hooks to hang lamps upon. Fig. 5 is a broken perspective view where but one standard is used. Fig. 6 is a 20 sectional elevation of the same.

This invention belongs to the class of danger signals used on the track of rail roads, and the novelty in the peculiar construction of the device and the combination of its several parts, all as will now be more fully set 25 out and explained.

In the embodiment of my invention, I employ standards or staffs A, adapted for detachable attachment to the rails of the track 30 or railway, each being split or slit from its lower end upward a suitable distance, as at a, to permit the branches or arms a' a', thereof thus formed to be sprung apart a limited extent in applying it to the rail. The branches 35 or arms a' a' are provided at their lower ends with springs, angular plates or feet a² adapted to conform to, and embrace, the tread and web of the rail B, thus providing for the seating or clamping of the standard or staff firmly 40 upon the rails for retention thereon without other assistance. Preferably each plate or foot a², extends up on the inside of the slit a, for a suitable distance, and is here secured by rivets or otherwise; thus to each part of 45 the arms or branches is secured one portion of the pair of spring clamps or feet to fit upon the tread. The ends a⁵, of each part of the spring clamps or feet flare slightly so as to provide easy means for the application of 50 each pair to the rail.

One of the branches or arms a' a', of the

standard or staff A, has secured thereto, horizontally, and near the lower end an approximately U-shaped clasp a³, embracing the opposite branch or arm of said standard to prevent the lateral displacement of either arm or branch in applying or attaching the standard to the rail. The spring a⁴, between the two arms will also assist to hold the two parts on the rail.

A signal C, made of any suitable material and of any desired color is attached at its ends or sides at any convenient point to the two standards, so that when the device is in position for use the signal stretches from side 65 to side of the rail road track and thus there will be no difficulty in its being observed from the engine cab of the approaching train.

In addition to the signal C, there are provided hooks D, extending outward from each 70 standard to afford means of hanging lanterns—one or both of said hooks can be used. The inner end of each of said hooks is movably fixed in the slot a⁵, of the standard so that when it is desired to roll up the signal, as in 75 Fig. 2, the hooks can be turned into said slots and thus be wholly out of the way of the part C.

In the modification shown in Figs. 5 and 6 E is a closure or cylinder held horizontally 80 about at its midlength to the shaft or standard A, a suitable distance below its upper end by means of a set or holding screw F and nut F', and a seating block or piece f, through which and the standard is passed said screw, 85 the latter being fixed to said block. The signal material or flag C, is connected at or along its lower edge to a spring-roller G, journaled in the cylinder or closure E, said flag being passed through a longitudinal slot e, in the 90 upper side of the cylinder or closure and having its upper edge connected to a suitable stiffening plate or rod c, having at its center a ring c', or other suspending device, adapted to be caught upon or engage a stud or projection a⁶, on the staff or standard, the same in the present instance being a screw projecting from the standard. Thus, with the staff or standard applied or clamped upon the rail of the track, by pulling upward upon the flag 100 and engaging its ring c', with the stud a⁶, it will be unrolled from the roller G, and with-

drawn from the closure or cylinder E, displaying it to view and causing it to serve as a danger signal to an approaching engine or train. When not desired for further use, and 5 by disengaging the ring c', from the stud a', the flag will be automatically rolled up into the closure or cylinder by the action of the spring-roller. It will thus be seen that the signal is adapted to be readily applied or attached to a rail of the track and held thereon without additional assistance while displaying the flag, and as quickly removed when not further needed.

Having thus described my invention, what 15 I claim, and desire to secure by Letters Patent, is—

1. The signal having the slotted staff or standard whose arms or branches are provided with angular plates or feet adapted to conform 20 to, and fit the rail of a railway track, substantially as described.

2. In a signal, the combination of the staff or standard, having spring feet suitably secured in and to the slotted lower end thereof, 25 as described, and adapted for application or attachment to the rails of a railway track, and the signal having its ends connected to said staff or standard, substantially as set forth.

3. The combination of the split staff or 30 standard having its arms or branches provided with angular plates or feet adapted to conform to, and embrace the rail of a railway track, the longitudinally slotted cylinder or closure having a seating-block and set-screw and nut

connection with said staff or standard, and 35 the signal or flag connected to a spring-actuated roller journaled in said cylinder or closure, said flag or signal having its upper end provided with a ring or like device adapted to engage a stud or projection on the staff 40 or standard, near its upper end, substantially as specified.

4. In a railway signal, the staff or standard having an approximately U-shaped clasp secured to one of its branches or arms and embracing the opposite branch or arm thereof, substantially as set forth. 45

5. In a railway signal, as described, the lamp hooks journaled in slots in the standards, substantially as and for the purposes set forth. 50

6. In a railway signal the combination of the standards having at their lower ends means for detachably connecting it with the rail and a signal adapted to be wound up when not in use, and reversible lamp hooks at the sides of 55 each standard, substantially as set forth.

7. In rail road signal standards each having slit ends provided with spring feet said ends being held together by means of a spring between them, substantially as and for the 60 purposes set forth.

In testimony whereof I affix my signature in presence of two witnesses.

FREEMAN HANSON.
